UNITED STATES PATENT OFFICE.

FREDERICK SCHMIDGALL, OF CINCINNATI, OHIO.

LATCH MECHANISM.

1,394,126.

Specification of Letters Patent. Patented Oct. 18, 1921.

Application filed March 29, 1921. Serial No. 456,609.

To all whom it may concern:

Be it known that I, FREDERICK SCHMIDGALL, a citizen of the United States, residing at Cincinnati, in the county of Hamilton and State of Ohio, have invented certain new and useful Improvements in Latch Mechanism, of which the following is a specification.

My invention relates to improvements in latch mechanism for refrigerator doors, cold-storage room and similar doors. One of its objects is to provide an improved latch mechanism suitable for doors of the above mentioned character. Another object is to provide an improved latch mechanism adapted to latch the door in closed position against rebound of the door when the door is closed, and to assist in opening the door after a partial opening of the door has been effected. Another object is to provide conveniently for opening the door from the inside, either by hand or by the impact of a truck against a latch releasing member. Another object is to provide an improved simple and reliable latch mechanism adapted to be applied either right-hand or left-hand as may be required. Another object is to provide an improved latch mechanism adapted to be employed either as a single latch or to be connected in parallel arrangement to latch the door at more than one point and with all the latches actuated in unison. My invention also comprises certain details of form combination and arrangement, all of which will be fully set forth in the description of the accompanying drawings, in which;

Figure 1 is a plan of a cold-storage room door and door frame with my improved latch mechanism applied thereto.

Fig. 2, is a vertical sectional detail on line 2—2 of Fig. 1.

Fig. 3, is a horizontal sectional detail on line 3—3 of Fig. 1.

Fig. 4, is a horizontal sectional detail on line 4—4 of Fig. 1.

Fig. 5, is a view similar to Fig. 4, on line 4—4 of Fig. 1, showing a different position of the latch.

Fig. 6, is a vertical sectional detail on line 6—6 of Fig. 1.

Fig. 7, is a perspective view of the latch keeper detached.

The accompanying drawings illustrate the preferred embodiment of my invention in which 15 represents door and 16 the door

frame of a refrigerator or cold-storage room door. The door is mounted by means of hinges 17 to swing relative to the door frame, and at its opposite edge is provided with a latch mechanism comprising latch mechanism or members carried on the door to engage latch keeper mechanism mounted upon the door frame.

The latch mechanism carried by the door 65 comprises a latch plate 18 rigidly attached to the door and provided with outwardly projecting lugs 19 and 20 between which is pivotally mounted a movable latch member 21 having a handle 22 by means of which it may be manually actuated in closing and 70 opening the door.

The latch plate 18 is also provided with a cylindrical stud 24 carried rigidly by the plate 18 and which overhangs the edge of the door and serves as a journal support for a cylindrical roller 25, which is rotatably mounted upon the stud 24. The stud 24 may be formed integral with the plate 18, or may be formed separately and detachably 80 and rigidly attached to the plate 18 as illustrated. A head 26 on the stud 24 serves to retain the roller 25 in place upon the stud 24. The forward end 27 of the movable latch member is crescent shaped in cross section and is movable to and fro from the roller 25, and its concave face closely fits the cylindrical, exterior of the roller 25.

The latch keeper mechanism carried by the door frame comprises a keeper 90 housing 30 rigidly attached to the door frame, a latch keeper 31 having double inclined faces 32 and 33 at its upper end to engage the roller 25 and the nose 27 of the movable latch member 21. 95 The latch keeper 31 is provided with a shank 34 which is sheathed within the housing 30 and is engaged by a coil spring 35 housed within the housing 30, and which serves to thrust the latch keeper yielding upward. The latch keeper engages the sides of a recess 36 in the housing 30 to prevent the latch keeper turning rotatably upon its longer axis with reference to the housing 30. The keeper 31 is also provided with a slot 37 through which passes a pin 38 which also passes through perforations in the casing 30 and serves to limit the upward movement of the latch keeper 31 relative to the housing 30. The lower end of the spring 35 bears upon an angle plate 40 which is adjustable vertically relative to 105 110

the door frame and housing 30, in order to variably adjust the tension of the spring 35 upon the latch keeper. The angle plate 40 is provided with a series of screw holes 5 through any one of which the screw 41 may be passed and seated in the door frame to lock the plate 40 rigidly to the door frame.

It is frequently desirable on large and heavy cold storage doors to employ two or 10 more latch mechanisms, say one near the top of the door and one sufficiently above the bottom of the door to be conveniently operated, while for smaller doors only a single latch mechanism is required. Where 15 only a single latch mechanism is to be used a plain cylindrical pivot pin may be employed to pivotally attach the latch member 21 to the ears 19 and 20. Where two or more latch mechanisms are to be employed 20 upon a single door and operated in unison by a single hand lever 22, I preferably provide a vertical connecting bar 45 of polygonal cross section which passes through corresponding polygonal recesses in the re- 25 spective upper and lower latch member 21, so that when one of said latch members 21 is actuated the other latch members 21 are also actuated through the connecting bar 45. In order to conveniently pivotally mount 30 the connecting bar with reference to the projections 19 and 20 of the respective latch members 18, I preferably provide sleeves 46 and 47 having cylindrical exteriors to be pivotally mounted relative to the projec- 35 tions 19 and 20 and with polygonal interiors to engage the polygonal faces of the bar 45, so that said sleeves 46 and 47 may turn with said rod 45. I have illustrated the lower end of the sleeve 47 as closed and 40 the lower end of the bar 45 stepped therein but the rod may pass entirely through the sleeve 47 and may be otherwise supported if desired.

In order that the door may be conveniently opened from the interior I provide a rod 50 passing endwise through the door and having a handle 51 threaded to its inner end, and preferably locked thereto by a set screw 52. The opposite end of the rod 50 is bent 50 at right angles and engages a slot 53 in the movable latch member 21, so that the latch member 21 may be actuated through the rod 50 from inside of the door, either by grasping and pushing or pulling on the handle 51, or by causing a truck to bump against the handle 50, or inner end of the rod 50. In practice the thickness of the doors varies, and by threading the handle 51 to the inner end of the rod 50, the handle 51 may be 60 be adjusted to the thickness of the door and the set-screw tightened, after which any excess in the length of the rod 50 may be cut off if desired. The rod 50 may be conveniently adjusted for either a right-hand 65 door or a left-hand door to the latch mem-

ber 21. A strap handle 55 is also preferably provided on the inside of the door for the convenience of the operator.

It is to be noted that the latch mechanism carried by the door and also that carried by the door frame can be applied without change to either a right-hand door or to a left-hand door, and that due to the extent to which the latch members 25 and 27 project over the edge of the door and their operative relation to the keeper, a considerable latitude in the adjustment of the latch mechanism upon the door and keeper mechanism upon the door frame is permissible without rendering the mechanism inoperative, and also that relative movement of said latch and keeper mechanism due to dampness and swelling or shrinking of the door or door frame is not liable to render the apparatus inoperative. 85

In operation when the door is closed the spring actuated keeper thrusts its upper end or nose yieldingly upwardly between the roller 25 and the latch member 27 to separate them, at the same time forcing the door into closed position by inclined face 32 directly forcing the roller 25, stud 24 and plate 18, and with them the door to closed position. The latch member 21 is also utilized as a lever to the end 27 of which force 90 is applied through the incline 33, and the opposite end of which at 21' bears upon the plate 18 to indirectly force the door to closed position. 95

When the latch member 21 is actuated by hand, the energy of the keeper in holding the door closed is overcome, and the roller 25 rides up the incline 32 of the keeper while the nose 27 rides up the incline 33 of the keeper until the roller 25 contacts with the concave face of the nose 27, and the latch member 21 has reached the limit of its movement, which carries the roller over the crest at the upper end of the keeper so that the roller 25 is in position to ride down the incline 33 of the keeper. The closing of the roller 25 and nose 27 together forces the keeper downwardly endwise against its spring 35, but as soon as the roller has 100 passed the crest of the keeper the keeper is thrust upward by its spring causing the roller to ride down the incline 33, thereby 105 forcing the door open. When the door is being closed, as soon as the roller has passed the crest of the keeper and commences to ride down the incline 32, the door is forced 110 closed by the action of the keeper, and any tendency of the door to rebound is absorbed resiliently by the keeper. One important 115 action of the roller and nose 27 jointly when they meet and separate is to insure the roller crossing instead of being hung up on the crest of the keeper. Other advantages of 120 my improved latch mechanism are that the thickness of the jamb 58 may vary con- 125 130

siderably without affecting the operativeness of the latch mechanism; the latch mechanism tends to lift or prevent sagging of the door both at the keeper, and also due 5 to the latch 21 moving outwardly instead of being pressed downwardly; and the constant yielding pressure to hold the door closed. If desired the door may be locked 10 by attaching a pad-lock to the keeper through the upper end of the slot 37.

The apparatus herein illustrated and described is capable of considerable modification without departing from the principle of my invention.

15 What I claim is:

1. A latch mechanism comprising a latch plate to be attached to a door having a roller journaled thereto and projecting into the path of a keeper yieldingly mounted upon the door frame, a latch lever movably mounted 20 upon said latch plate and provided with a nose movable to and from said roller and having a recess to receive a portion of the face of said roller and a resiliently supported 25 latch keeper having an upwardly directed nose with outwardly directed inclined faces at opposite sides thereof, the nose of said latch keeper being interposed between said roller and latch member to hold the door in 30 closed position.

2. A latch mechanism comprising a latch plate to be attached to a door having a roller journaled thereto and projecting into the path of a keeper yieldingly mounted upon 35 the door frame, a latch lever movably mounted upon said latch plate and provided with a nose movable to and from said roller, a latch keeper housing mounted upon the door frame, a latch keeper resiliently supported 40 by said housing and movable at the opening and closing of said door out of the path of said roller, said latch keeper having a nose with outwardly directed inclined faces over 45 which said roller is adapted to travel in opening and closing said door.

3. A latch mechanism comprising a latch plate to be attached to a door having a roller journaled thereto and projecting into the path of a keeper yieldingly mounted upon the door frame, a latch lever movably mounted 50 upon said latch plate and provided with a nose movable to and from said roller, a latch keeper housing mounted upon the door frame, a latch keeper resiliently supported by said housing and having a limited movement relative to said keeper housing at the opening and closing of said door to enable 55 said keeper to move out of the path of said roller, said latch keeper having two inclined faces meeting in a nose over which inclined faces and nose said roller is adapted to travel in opening and closing said door, and one of said inclined faces serving to engage 60 said roller to hold the door in closed position.

4. A latch mechanism comprising a latch plate to be attached to a door having a roller journaled thereto and projecting into the path of a keeper yieldingly mounted upon the door frame, a latch lever movably mounted upon said latch plate and provided with a nose movable to and from said roller, a latch keeper housing mounted upon the door frame, a latch keeper resiliently supported by said housing and having a limited movement relative to said keeper housing at the opening and closing of said door to enable 70 said keeper to move out of the path of said roller, and means to adjust the resilient tension on said latch keeper, said latch keeper having two inclined faces meeting in a nose over which inclined faces and nose said roller is adapted to travel in opening and closing said door, and one of said inclined faces serving to engage 75 said roller to hold the door in closed position.

In testimony whereof I have affixed my signature.

FREDERICK SCHMIDGALL.
